UNITED STATES PATENT OFFICE.

DANIEL C. CARR, OF CHICAGO, ILLINOIS.

NECKTIE GUIDE.

Application filed March 8, 1927. Serial No. 173,719.

This invention relates to devices used in connection with collars and the attachment thereof to the rear portion of the shirt neckband, and deals more particularly with the means for the guiding of the necktie, being in that connection an improvement over the collar attaching device patented by me July 1, 1924, No. 1,499,570.

The main object of my improvement is to simplify the manipulation of the device for the insertion and removal of the necktie.

A further object is to create a greater opening for the same purpose.

A final, but nevertheless important object of the invention is to simplify the construction of the device in order to reduce the cost of its manufacture.

With the above objects in view and any others that may suggest themselves from the specification and claims to follow, a better understanding of the invention may be gained by reference to the accompanying drawing, in which—

Figure 1 is a side elevation of the improved device showing its application.

Fig. 2 is a perspective view thereof in closed position;

Fig. 3 is a similar view, in open position, and

Fig. 4 is a magnified section of the medial portion of the device, such as taken between the lines A and B in Figure 1.

Referring specifically to the drawing, the numeral 5 generally designates a collar having inner and outer folds 6 and 7, respectively, the inner fold being provided with the usual button hole 8.

The collar may be attached to the neck band 10 by means of the improved fastener which, as illustrated in Figs. 2 and 3, consists principally of a length of metal 11 having one end bent upon itself to provide a shirt neckband engaging hook 12. The lower portion of the length of metal is offset as indicated at 14 and is extended through the button hole 8 whereby to place the hook 12 in position to engage the lower edge of the shirt neckband 10. More specifically, the hook 12 is designed to engage the outer fold of the said shirt neckband and it is believed to be obvious that the latter is ordinarily provided with a button hole opening through which the rear collar button is extended. However, in accordance with this invention there is no need for the rear collar button

hole as the hook directly engages the neckband.

The upper portion of the length of metal is formed with an open ended loop 16 to slidably receive the necktie 17 and thereby support the tie at a point above the lower edges of the inner and outer folds of the collar. Consequently the tie may freely slide between the folds.

The loop 16 is supplemented by a latch 18 having a bottom return bend 19 in the direction of the length 11 and secured to the same immediately above the offset 14, by a loose rivet 20, which forms a pivot-element for the latch. The latter overlaps the end 66 of the loop 16 from the inside, and normally forms a closure therefor to retain the tie within the loop. However, when the tie is to be removed, the latch may be swung in the direction of the arrows in Fig. 2 to locate it in a transverse position, as shown in Fig. 3. A wide opening is now created for the easy removal—or reinsertion—of the tie relative to the loop. The latch could, of course, have been swung in the opposite direction to secure the resultant opening.

In order that the latch 18 may remain in closed position when set, that part thereof which cooperates with the end of the loop 16 is pressed with an inward bulge or protuberance 18^a which seats in an opening 16^a in the loop 16, correspondingly located. When the latch is swung to close, the tension of the affected sections causes them to lock with a click and remain so until manually separated.

The back of the hook 12 is also pressed with a rearward bulge or point 12^a which, bearing against the inner fold of the collar, checks possible lateral play of the device 95 relative to the collar or shirt neckband.

It will be seen that the new device is an improvement over my patented one mainly in the provision of the novel latch, which furnishes a wide opening for the insertion 100 or removal of the necktie. In the novel embodiment the latch is easy to operate, and one need not pay close attention in handling it; in fact, the only attention required is to see that the necktie band faces in the proper 105 direction, since the manipulation of the necktie and the guide does not require visual assistance. The novel structure also provides more room for the free action of the necktie, and the rounding of the inner head 110

20^a of the rivet 20—as clearly shown in Fig. 4—precludes the presence of an obstruction at that site, so that the necktie is not hindered in its action but rather eased by being spaced from the collar folds. The novel latch is of course, very simple and materially reduces the cost of producing the article.

While I have illustrated and described the novel improvement in the preferred form, 10 it will be seen that the same is capable of many minor changes and refinements, and I therefore wish to claim all such changes and refinements as coming within the scope and spirit of the appended claims.

15 I claim:—

1. A necktie guide comprising a body having one end portion offset for extending through the button hole in the inner fold of a collar and being provided with means 20 to engage the neckband of a shirt, the other end portion of the body being formed with an open ended loop adapted to slidably receive and support a necktie, and a latch pivoted to said body to swing in a plane 25 transverse to that of the loop and engage the said open end of the latter for normally closing the same.

2. A necktie guide comprising a body having one end portion offset for extending 30 through the button hole in the inner fold of a collar and being provided with means to engage the neckband of a shirt, the other end portion of the body being formed with an open ended loop adapted to slidably receive a necktie, and a U-shaped latch pivoted 35 to said body to swing in a plane transverse to that of the loop and complete the latter when engaging the said open end of the same to retain and support said necktie.

40 3. A necktie guide comprising a body having one end portion offset for extending through the button hole in the inner fold of a collar and being provided with means to engage the neckband of a shirt, the other 45 end portion of the body being formed with

an inverted U-shaped portion adapted to slidably receive and support a necktie, and a U-shaped latch having one arm transversely pivoted to said body and the other normally in engagement with said open end of the inverted U-shaped portion whereby to close the same and confine the tie therein.

4. A necktie guide comprising a body having one end portion offset for extending through the button hole in the inner fold of a collar and being provided with means to engage the neckband of a shirt, the other end portion of the body being formed with an open ended loop adapted to slidably receive and support a necktie, and a latch pivoted to said body to swing in a plane transverse to that of the loop and engage the said open end of the latter for normally closing the same, said engagement incorporating self-locking means.

5. The structure of claim 1, with an enlargement carried by the latch and adapted to seat in a recess in the open end of the loop, whereby to lock the latch in closed position.

6. A necktie guide comprising a loop to retain and support a necktie, an extension of the loop adapted to pass through the buttonhole of a collar and engaging the neckband of a shirt, and a projection extending from said extension to frictionally engage the collar at a point spaced from the button hole to prevent sliding or swinging movement of the loop relative to the collar.

7. A necktie guide comprising a body having collar engaging means at one end and the other end formed in a reverted open ended loop adapted to slidably receive and support a necktie, and a latch pivoted to said body to swing in a plane transverse to that of the loop and engage the said open end of the latter for normally closing the same.

In testimony whereof I affix my signature.

DANIEL C. CARR.
